United States Patent Office

Des. 217,334
Patented Apr. 28, 1970

217,334

COMBINED BOTTLE AND OVERCAP THEREFOR

Richard L. Weckman, Perrysburg, Ohio, assignor to Owens-Illinois, Inc., Toledo, Ohio, a corporation of Ohio

Filed Feb. 19, 1969, Ser. No. 15,846

Term of patent 14 years

Int. Cl. D9—01

U.S. Cl. D9—117

FIG. 1

FIG. 2

FIG. 3

FIG. 5

FIG. 6

FIG. 1 is an elevational view of a combined bottle and overcap therefor showing my new design; the side opposite that seen being the same in appearance as the side shown;

FIG. 2 is an elevational view looking from the right of FIG. 1, the side opposite that seen being the same in appearance as the side shown;

FIG. 3 is a top plan view;

FIG. 4 is a view similar to FIG. 1 with the overcap removed, the side opposite that seen being the same in appearance as the side shown;

FIG. 5 is a top plan view thereof; and

FIG. 6 is an elevational view looking from the right of

FIG. 4, the side opposite that seen being the same in appearance as the side shown.

I claim:

The ornamental design for a combined bottle and overcap therefor, substantially as shown and described.
